UNITED STATES PATENT OFFICE.

JULIUS J. LORZING, OF ELMFSORD, NEW YORK.

VALVE STRUCTURE FOR FOUNTAIN-BRUSHES.

1,168,893.

Specification of Letters Patent. Patented Jan. 18, 1916.

Original application filed July 28, 1913, Serial No. 781,583. Divided and this application filed March 20, 1915. Serial No. 15,948.

To all whom it may concern:

Be it known that I, JULIUS J. LORZING, a citizen of the United States, residing at Elmsford, in the county of Westchester and 5 State of New York, have invented certain new and useful Improvements in Valve Structures for Fountain-Brushes, of which the following is a specification, reference being had to the accompanying drawings.

10 This invention comprehends certain new and useful improvements in brushes, and particularly to brushes of the fountain type, this case being a divisional of the application which was filed July 28, 1913, Serial 15 No. 781,583, and which eventuated in Patent No. 1,091,888 which was issued March 31, 1914.

The original application above identified, embodied a particular construction of 20 combined brush tuft socket and outlet tube, in addition to the features which related strictly to a fountain brush, and in that application it was elected to retain the claims drawn to the tuft fastener or combined brush tuft socket and outlet tube.

The present case embodies the features which relate particularly to the valve, and the invention has for its primary object a durable and efficient construction of device of this character, the parts of which 30 may be very easily manufactured and readily assembled and which will not be liable to get out of order, but capable of being easily manipulated. And the invention also 35 aims to generally improve devices of this class so as to render them more useful and commercially desirable.

With these and other objects in view, as 40 will more fully appear as the description proceeds, the invention consists in certain constructions, arrangements and combinations of the parts that I shall hereinafter fully describe and claim.

For a full understanding of the invention, 45 reference is to be had to the following description and accompanying drawing, in which,

Figure 1 is a side elevation partly broken away and partly in section, of a brush embodying the improvements of my invention. Fig. 2 is a longitudinal sectional view of another embodiment of the invention. Fig. 3 is a transverse sectional view on the line 3—3 of Fig. 1. Fig. 4 is an enlarged 50 longitudinal sectional view of the valve.

Corresponding and like parts are referred to in the following description and designated in all of the views of the accompanying drawing by like reference characters.

Referring to the drawing, the numeral 1 60 designates a brush head which in the present instance, is designed to form part of a brush adapted for painters' use, said head being formed of wood or metal and being made hollow so as to constitute a distributing 65 chamber 2 for holding a liquid such as paint, water, liquid soap, or any other fluid. The liquid is conveyed into the distributing chamber 2 through a duct 3 leading from a tank or reservoir which, in that embodiment 70 of the invention illustrated in Fig. 1, is formed by the handle 4 of the brush, said combined reservoir and handle being formed with a side opening which is closed by any desired device as, for example, the screw cap 75 5 shown.

The paint or other liquid is fed to the bristles 6 by means of outlet tubes, as shown, some of said tubes being designated 7 and comprising the combined brush tuft sockets 80 and outlet tubes which form the subject matter of Patent No. 1,091,888, hereinbefore referred to. For a further understanding of this combined brush tuft socket and outlet tube, reference to that patent should be 85 had.

In order to control the passage of the liquid from the reservoir 4 to the distributing chamber 2, I provide an improved valve 8. This valve is preferably of cylindrical form 90 and is internally screw-threaded, at both ends, as at 9, to receive the stub end of the brush head and the adjoining end of the combined reservoir and handle 4. The valve is provided with a valve seat 10 and movable 95 valve elements 11 and 12. The valve seat 10 and valve element 11 are centrally apertured, while the valve element 12 is eccentrically apertured, as at 13. The valve element 12 is provided with a stem 14 extending outwardly through an aperture in the wall of the valve casing, a finger piece 15 being secured on the outer end of the valve stem, and a spring 16 being seated between the finger piece and the outer wall of the casing. It 100 will be seen that the spring normally holds the valve 12 in closed position, the apertures in the valve seat 10 and valve 11 being out of communication with the valve opening 13, but when the finger piece is pressed in- 110

wardly, the valve openings are brought into registry, so that the liquid may pass from the reservoir 4 into the duct 3 and thence to the distributing chamber 2. It is obvious 5 that the pressure of the liquid against the movable valve element 11 keeps it snugly seated upon the adjoining surface of the valve element 12 so that leakage through the valve is effectively prevented. Furthermore, as very clearly illustrated in Figs. 2 10 and 4, it will be seen that the combined tank and handle, where it screws into one end of the valve casing, will engage the movable valve element 11 and securely hold it in 15 place.

It is to be understood that my invention is not limited to any particular construction and arrangements of parts so far as the formation or style of brush head and reservoir are concerned. For example, the valve 20 may be embodied in a scrubbing brush, like the one illustrated in my patent hereinbefore identified, or in a dauber as illustrated in Fig. 2 of the accompanying drawing. In 25 this dauber, there is a relatively large combined socket and outlet tube, although, obviously, several smaller members of this kind may be employed. As illustrated, the dauber consists of a hollow brush head 1' 30 provided with a lateral extension or pipe connection 2" onto which is secured one of the valves 8 illustrated in detail in Figs. 3 and 4. The handle 4' of the dauber is hollow and constitutes a reservoir for suitable 35 liquid to be used in moistening the paste which is to be applied to the shoes or other articles to be daubed, said combined handle and reservoir being in screw-threaded engagement with the valve 8 and communicating 40 with the distributing chamber 2' when the valve stem 14 is pressed.

From the foregoing description in connection with the accompanying drawing, the operation of my improved fountain brush 45 valve will be apparent. In the practical use of the device, whenever the valve is opened, the liquid will flow from the reservoir to the distributing chamber of the brush head, and thence be conducted to the bristles to be applied in the ordinary manner. When the 50 operator releases the valve by the pressure

of his thumb or finger, the valve will automatically close through the instrumentality of its spring.

It is to be understood that the invention 55 is not limited to the feature of confining the reservoir to the handle of the device, but that the supply tank or reservoir of any desired character separate and distinct from the brush, may be operatively connected 60 thereto in any desired way, so as to supply the desired fluid.

While the accompanying drawing illustrates what I believe to be the preferred embodiment of my invention, it is to be understood that the invention is not limited thereto, but that various changes may be made in the construction, arrangements and proportions of the different parts without departing from the scope of the invention as defined in the appended claim.

What is claimed, is:

In a valve adapted for use as a coupling between two conduit members, a valve casting having internal threads at each end to 75 receive the conduit members, an internal valve seat formed in the valve body and provided with an orifice, a relatively fixed valve member provided with an orifice which alines with the orifice in the valve seat, an internal 80 shoulder formed in the valve body, said fixed valve being disposed to abut against said shoulder and being removable from the valve body, the inner end of one conduit being engageable with the valve body for holding the 85 same against the shoulder, whereby the fixed valve member is maintained in parallel spaced relation to the inner face of the valve seat, and a movable member slidably mounted between the valve seat and the fixed valve, 90 said movable valve member being provided with a passage, and means normally holding the valve member in closed position, wherein the passage is out of alinement with the orifices of the valve seat and fixed valve 95 member.

In testimony whereof I hereunto affix my signature in the presence of two witnesses.

JULIUS J. LORZING.
